ROUNDING AND CHANNELING MACHINE

Filed April 26, 1930

UNITED STATES PATENT OFFICE

OSCAR L. SHERMAN, OF MEDFORD, AND ADELORD BOURGEOIS, OF SWAMPSCOTT, MASSACHUSETTS, ASSIGNEES TO UNITED SHOE MACHINERY CORPORATION, OF PATERSON, NEW JERSEY, A CORPORATION OF NEW JERSEY

ROUNDING AND CHANNELING MACHINE

Application filed April 26, 1930. Serial No. 447,701.

This invention relates to improvements in machines for operating upon the soles of shoes and is herein illustrated as embodied in a rounding and channeling machine of the 5 type disclosed in United States Letters Patent No. 600,883, granted March 22, 1898, upon application of W. C. Meyer and Z. T. French. The invention is set forth hereinafter with particular reference to its application to the 10 rounding and channeling of soles which have been applied to shoes in the process of repairing the shoes. The invention is not necessarily limited, however, in its application to repair work nor to machines for performing 15 both rounding and channeling operations. Neither is the invention limited to embodiment in machines of the particular type disclosed in the patent referred to.

Machines of the type referred to are particularly designed for operation upon welt shoes and to this end each machine is provided with a fixed "work support" or so-called "crease guide" arranged to enter the 20 welt crease of a shoe to assist in supporting the shoe in position to be operated upon. When such a machine is used in connection with the repairing of welt shoes the machine is also provided with means in the nature of an edge gage or guide for engaging the 25 previously trimmed edge of the welt of a shoe to guide the shoe as it is fed past the operating instrumentalities of the machine. Such machines, however, are not adapted to operate upon the soles of McKay-sewed shoes of the 30 type having no welt or its equivalent to be engaged by the edge gage and, further, for the reason that, at the time when the trimming operation is to be performed, there is in such shoes no definite crease between the 35 sole and the upper with which the crease guide of the machine may effectively co-operate in guiding the shoe.

In view of the foregoing, one object of the 40 present invention is to provide a machine which will be adapted to operate progressively along the bottom margins of shoes not only of the type wherein a welt or other previously trimmed bottom member is provided for attachment to the tread sole but also of 45 the type wherein no welt or equivalent shoe

bottom member is provided, and wherein the tread sole is secured directly to the upper as, for example, in McKay-sewed shoes, turn shoes and shoes in which adhesive is employed as the sole attaching means.

To the accomplishment of this object, and in accordance with the present invention, the illustrated machine is provided, not only with an edge gage for guiding a shoe by engagement with the edge of a welt or other shoe 55 bottom member, but also with an upper gage for guiding a shoe by engagement with the shoe upper, thus adapting the machine for use in operating upon shoes having no welt edge or other shoe bottom edge capable of being 60 engaged by an edge gage. To this end, a feature of the invention consists in the provision, in a machine having means for operating upon the sole of a shoe as the shoe is fed 65 to advance its sole margin progressively past 70 said means, of an edge gage movable into and out of position to guide the shoe by engagement with the edge of a shoe bottom member 75 while the shoe is being fed and operated upon, and an upper gage movable into and out of 80 position to guide a shoe by engagement with the shoe upper as the shoe is being fed and operated upon, said gages being so connected together and so arranged relatively to each 85 other that when either of the gages is operatively positioned the other gage will be inoperatively positioned. In the illustrated 90 machine the operating means comprises a rounding knife and a channeling knife and the work is supported and fed by the co-operation of means comprising a feed plate adapted to engage the exposed face of a welt or other projecting shoe bottom margin and a reciprocatory work support arranged to engage the tread face of the shoe bottom. The illustrated edge gage comprises an arm having an end face for engaging the edge of the previously trimmed welt of a shoe, while the illustrated upper gage comprises an arm carrying a roll for engaging the upper of a shoe in a location close to the shoe bottom. The means herein shown for connecting the gages comprises a rocker stud to the opposite 95 ends of which the gage arms are secured, the rocker stud being journaled in the feed plate 100

and the gage arms extending radially from the rocker stud and being separated by a radial angle such that when either gage is positioned for operation upon a shoe the other gage will be inoperatively positioned. The 5 illustrated edge gage is located between the feed plate and the rounding knife and is provided with an opening or slot arranged to permit the rounding knife to move through the edge gage into engagement with a cutting block in the rear face of the feed plate. As 10 illustrated, also, manually releasable means is provided for locking the rocker stud in two positions in one of which the edge gage 15 is operatively positioned and in the other of which the upper gage is operatively positioned.

The invention will be explained with reference to the accompanying drawing in 20 which

Fig. 1 is a view, in front elevation, of so much of a rounding and channeling machine as is necessary to illustrate the application of the present invention thereto, the machine being shown in operation upon the sole of a welt shoe;

Fig. 2 is a view, partially in side elevation and partially in section, of the portion of the machine shown in Fig. 1, this view also showing the machine in operation upon a welt shoe;

Fig. 3 is a view similar to Fig. 2 but showing the machine in operation upon a McKay-sewed shoe; and

Fig. 4 is a detailed perspective view of the edge gage used for guiding a welt shoe.

In the drawing, the invention is shown as embodied in a rounding and channeling machine of the general type disclosed in Letters 40 Patent No. 600,883, hereinbefore referred to. The illustrated machine is provided with a four-motion feed plate 10 arranged to engage the upper surface of the welt, in a welt shoe (or the corresponding portion of the projecting sole margin of a shoe in which no welt is employed such, for example, as a McKay-sewed shoe or a turn shoe); a "sole support" 45 in the form of an anti-friction roll 12 which is movable back and forth to co-operate with the feed plate 10 in feeding the work; a fixed "work support" or "crease guide" 14 shaped to enter the usual crease between the welt or sole margin and the upper of a shoe; a vibratory rounding knife 16 which is movable toward the feed plate to trim the outsole of the shoe; and a channel knife 18 which is movable with the sole support. The above-described parts are substantially the same in construction and have substantially the same mode of 50 operation as corresponding parts disclosed in said patent and, accordingly, no further description of these parts will be given herein.

To adapt the present machine for use in operating both upon welt shoes and upon 55 McKay-sewed shoes (or other shoes in which

the tread sole is directly secured to the upper) for the purpose of rounding or rounding and channeling soles which have been applied to the shoes in the process of repairing them, the machine, in accordance with the present invention, is provided with an edge gage 20 which is movable into position for use when the machine is operating upon welt shoes, and an upper gage 22 which is movable into position for use when the machine is operating upon McKay-sewed shoes or other shoes in which no welt or equivalent shoe bottom element is employed. As herein shown, the welt edge gage 20 is located at the rear of the feed plate 10 while the upper gage 22 is located in front of the feed plate and the gages 20 and 22 are secured respectively to the rear and front end portions of a rocker stud 24 which is mounted to turn in a suitable bearing formed in the upper portion of the feed plate.

The illustrated welt edge gage 20 comprises a thin plate the upper portion of which is integrally connected with the rear of the rocker stud 24 in such a way that the plate extends radially from the stud at right angles to the axis of the latter. At its lower or outer end the plate 20 is provided with an edge face 28 (Fig. 4) which is adapted to engage the trimmed edge of the welt of a shoe which is being repaired. The plate 20 is further provided near its outer end with an opening or slot 30 through which the rounding knife is adapted to vibrate.

The illustrated upper gage 22 consists of an anti-friction roll which is mounted to turn idly on the outer end of an arm 34 the opposite end of which is rigidly secured to the front end of the rocker stud 24 by means of a screw 35. The front end of the rocker stud 24 is flattened, as indicated at 36 in Fig. 4, to prevent radial displacement of the arm 34 thereon. As shown, the periphery of the gage roll 22 is transversely concave to conform approximately to the curvature of the upper of a shoe in the vicinity of the crease between the upper and the sole. The arm 34 is bent, as shown at 38, so as to position the gage roll 22 close to the work support 14 so that the roll may engage the upper as close as practicable to the sole.

The welt gage plate 20 and the upper gage arm 34 are positioned on the rocker stud 24 so that they extend in different radial directions relatively to the stud. As shown, the two gage arms are separated radially by an angle of substantially 90°. Thus, when either of the gages is operatively positioned the other gage will necessarily occupy an inoperative out-of-the-way position.

Provision is made for locking the rocker stud 24 in two positions in one of which the welt edge gage 20 is operatively positioned and in the other of which the upper gage 22 is operatively positioned. This locking is effected by engagement of the lower end of a

lock bar 40 with one or the other of two notches 42 and 44 formed in the periphery of a disk 46 which is fast on the rocker stud 24. The disk 46 is clamped between the arm 34 of the upper gage and shoulders 48 on the rocker stud by means of the screw 35. As shown, the lock bar 40 is pivotally mounted between two ears 52 formed on the feed plate 10, the bar 40 being pivoted upon a pin 54 the ends of which extend through the ears 52. The lock bar 40 is yieldingly held in locking position by means of a spring 56 one end of which is seated in a socket in the feed plate while the other end of the spring bears against the upper end of the lock bar. As shown at 58, the upper end of the lock bar is enlarged to adapt it to be conveniently depressed by the operator against the action of the spring to release the lock bar from locking engagement with the disk.

To adapt the machine for operating upon welt shoes the welt edge gage is positioned, as shown in Figs. 1 and 2, with its lower edge face located behind the feed plate in position to engage the trimmed edge of a welt, such as the welt W of the shoe S. When thus positioned the slot 30 in the edge gage plate is located in the path of vibratory movement of the rounding knife 16, thus permitting the knife, after cutting through the outsole O of the shoe S, to continue its forward stroke until it engages a cutting block 60 inserted in the rear face of the feed plate. The reason for permitting the rounding knife to move into contact with the cutting block 60 on the feed plate will be made apparent later in describing the operation of the machine in connection with McKay-sewed shoes. When the gages are adjusted as shown in Figs. 1 and 2, the machine is adapted to trim an outsole which has been applied to a welt shoe in the process of repairing the shoe so that the trimmed sole edge will bear a desired definite relation to the previously trimmed edge of the original welt. As shown, the newly applied outsole is trimmed slightly wider than the welt to allow sufficient surplus of outsole margin for subsequent finishing operations.

To adapt the machine for operating upon McKay-sewed shoes, turn shoes, or shoes having cemented soles, it is only necessary to unlock the rocker stud 24 by depressing the upper end 58 of the lock bar 40 to disengage the lock bar from the notch 44 in the disk 46 and to turn the stud 24 so as to reverse the position of the gages, thus bringing the upper gage 22 into operative position and at the same time throwing out of operative position the welt edge gage 20. When the upper gage 22 has reached operating position, the spring 56 will cause the lock bar 40 automatically to engage the notch 42 in the disk 46 thereby locking both gages in the positions shown in Fig. 3. The upper gage 22 will then be located to guide a shoe by engagement with the

shoe upper at points adjacent to the sole thus insuring that the trimmed edge of the sole will bear a desired definite relation to the contour of the last or other form which is provided within the shoe to support the upper against the thrust of the gage. It will be evident that the rounding knife will trim the sole of a McKay-sewed shoe with a chopping action the knife cutting against the cutting block 60 in the feed plate.

When the upper gage 22 is in operative position the machine may readily be adapted for operation upon welt work merely by manually releasing the lock bar 40 and readjusting the gages to move the edge gage 20 into operative position, thereby inoperatively positioning the upper gage and moving the notch 44 into position to be engaged by the lock bar 40 for the purpose of locking both gages in the positions last specified.

The fixed "crease guide" or "sole support" 14 has no positive guiding function, when the machine is operating upon either welt, turn, or McKay-sewed shoes, other than indicating to the operator whether the shoe is being held in proper relation to the operating instrumentalities of the machine, the actual guiding of the work being effected by the edge gage 20, in the case of welt shoes, or by the upper gage 22, in the case of turn or McKay-sewed shoes. The sole support 14, however, does co-operate with the work support 12 to support the work in position to be operated upon.

Having described the invention, what we claim as new and desire to secure by Letters Patent of the United States is:

1. In a machine having means for operating upon the sole of a shoe as the shoe is fed to advance its sole margin progressively past said means, in combination, an edge gage movable into and out of position to guide the shoe by engagement with the edge of a shoe bottom member while the shoe is being fed and operated upon, and an upper gage movable into and out of position to guide a shoe by engagement with the shoe upper as the shoe is being fed and operated upon, said gages being so connected together and so arranged relatively to each other that when either of the gages is operatively positioned the other gage will be inoperatively positioned.

2. In a machine having means for operating upon the sole of a shoe as the shoe is fed to advance its sole margin progressively past said means, in combination, an edge gage movable into and out of position to guide the shoe by engagement with the edge of a shoe bottom member while the shoe is being fed and operated upon, and an upper gage movable into and out of position to guide a shoe by engagement with the shoe upper as the shoe is being fed and operated upon, said gages being relatively fixed in such relation

that when either gage is operatively positioned the other gage will be inoperatively positioned.

3. In a machine having means for operating upon the sole of a shoe and means for feeding a shoe to advance its sole margin progressively past said means, the combination with said feeding and operating means of an edge gage movable in directions lengthwise of the sole edge into and out of position to guide a shoe by engagement with the edge of a shoe bottom member while the shoe is being fed and operated upon, an upper gage movable into and out of position to guide a shoe by engagement with the shoe upper while the shoe is being fed and operated upon, and connections between said gages constraining them for movement simultaneously in one direction to position one of the gages in work-engaging position and for movement simultaneously in another direction to position the other gage in work-engaging position.

4. In a machine having means for operating upon the sole of a shoe and means for feeding a shoe to advance its sole margin progressively past said means, the combination with said feeding and operating means of an edge gage rotatable into and out of position to guide a shoe by engagement with the edge of a shoe bottom member while the shoe is being fed and operated upon, and an upper gage rotatable into and out of position to guide a shoe by engagement with the shoe upper while the shoe is being fed and operated upon, said gages being constructed and arranged to turn simultaneously so as to move one of the gages out of work-engaging position when the other gage is moved into work-engaging position.

5. In a machine having an edge gage for guiding a shoe by engagement with the edge of a shoe bottom member during the performance of an operation upon the sole of the shoe, in combination, a support for the edge gage, said support being movable to move the edge gage into and out of operative position, and an upper gage mounted upon said support and adapted to be moved by movement of said support into and out of position to guide a shoe by engagement with the shoe upper, said gages being so arranged on said support relatively to each other that when one of the gages is operatively positioned the other gage will be inoperatively positioned.

6. In a rounding machine, in combination, work supporting and feeding means including a feed plate, a rounding knife, a movable edge gage located at one side of the feed plate, a movable upper gage located at the other side of the feed plate, and a connection between said gages constructed and arranged to move the edge gage out of operative position when the upper gage is moved into operative position and to move the upper gage

out of operative position when the edge gage is moved into operative position.

7. In a rounding machine, in combination, work supporting and feeding means including a feed plate, a rounding knife adapted to cut against the feed plate, a movable edge gage located at one side of the feed plate and having an opening therein to permit the passage of the rounding knife therethrough, a movable upper gage located at the other side of the feed plate and offset relatively to the edge gage, and a connection between said gages constructed and arranged to move the edge gage out of operative position when the upper gage is moved into operative position and to move the upper gage out of operative position when the edge gage is moved into operative position.

8. In a machine for rounding and channeling the soles of shoes, the combination with the rounding and channeling means of a gage carrier movable between two positions, an edge gage for guiding a shoe by engagement with the edge of a shoe bottom member, and an upper gage for guiding a shoe by engagement with the shoe upper, said gages being secured to said carrier and arranged thereon so that when the carrier is moved into one of said positions the edge gage will be operatively positioned and the upper gage will be inoperatively positioned and when the carrier is moved into the other of said positions the upper gage will be operatively positioned and the edge gage will be inoperatively positioned.

9. In a machine for trimming the soles of shoes, the combination with work supporting and feeding devices and a trimming knife, of a gage carrier movable between two positions, an edge gage and an upper gage arranged in such spaced apart relation on said carrier that movement of the carrier into one of said positions will operatively position the edge gage and inoperatively position the upper gage while movement of the carrier into the other of said positions will operatively position the upper gage and inoperatively position the edge gage, and means for locking the gage carrier in each of said positions.

10. In a machine for trimming the soles of shoes, an edge gage adapted to guide a shoe by engagement with the edge of the welt, an upper gage adapted to guide a shoe by engagement with the shoe upper, said gages being connected to move in unison in one direction to move the edge gage into operative position and the upper gage out of operative position and in another direction to move the upper gage into operative position and the edge gage out of operative position, and positive means for locking said gages in both operative and inoperative positions.

11. In a rounding machine, the combination with a rounding knife and work sup-

- porting and feeding instrumentalities, of a movable gage adapted to guide a shoe by engagement with a previously trimmed edge of the shoe bottom, a second movable gage 5 adapted to guide a shoe by engagement with the shoe upper, and a rigid connection between said gages for throwing either of said gages out of operative position when the other gage is moved into operative position.
- 10 12. In a rounding machine having a feed plate and a rounding knife, a rocker stud journaled in the feed plate, an edge gage member projecting radially from said rocker stud, and an upper gage member projecting 15 radially from the rocker stud at a different angle from that of the edge gage, said rocker stud being rotatable into either of two positions to locate either of said gage members in position for operative engagement with 20 a shoe.
13. In a rounding machine having a feed plate and a rounding knife, a rocker stud journaled in the feed plate, an edge gage member projecting radially from said rocker 25 stud, an upper gage member projecting radially from the rocker stud at a different angle from that of the edge gage, said rocker stud being rotatable into either of two positions to locate either of said gage members in 30 position for operative engagement with a shoe, and means for locking said stud in either of said positions.
14. In a rounding machine having a feed plate arranged to engage a projecting shoe 35 bottom margin at the side adjacent to the shoe upper, a rounding knife arranged to cut against the work-engaging face of the feed plate, a gage located adjacent to said face of the feed plate and movable into and 40 out of position to guide a shoe by engagement with the edge of a shoe bottom member, said gage being slotted to permit the passage of the rounding knife therethrough, a second gage movable to and from position to guide 45 a shoe by engagement with the shoe upper, and a connection between said gages constructed and arranged to move one gage out of operative position when the other is moved into operative position.
- 50 15. In a rounding machine having work supporting and feeding means including a feed plate for engaging a projecting shoe bottom margin at the side adjacent to the shoe upper, in combination, a rounding knife 55 arranged to cut against the rear face of the feed plate, a gage movable into and out of operative position at the shoe-bottom-engaging side of the feed plate to guide a welt shoe by engagement with the edge of the welt, 60 said gage being slotted to permit the passage therethrough of said knife, a second gage located adjacent to the opposite side of the feed plate and adapted to guide a shoe by engagement with the shoe upper, and a 65 rocker stud journaled in the feed plate to

which said gages are secured, the gages being relatively positioned so that when either one is operatively positioned the other will be inoperatively positioned.

In testimony whereof we have signed our 70 names to this specification.

OSCAR L. SHERMAN.
ADELORD BOURGEOIS.
